WELDED SHEET METAL GOLF SHAFT AND
METHOD OF MAKING THE SAMEHerbert C. Lagerblade, Bristol, Conn., assignor to
The Horton Manufacturing Company, a cor-
poration of Connecticut

Application October 8, 1932, Serial No. 636,851

22 Claims. (Cl. 29—156)

My invention relates to welded sheet metal golf shafts and methods of making the same.

It has heretofore been proposed to produce polygonal or hexagonal shafts of this type having a ground off strip of welding material, such as taught in the Emmet and Thorpe Patent 1,550,153 or my prior Patent 1,783,802, disposed longitudinally of the middle of one of the flat sides, and a heavy welded section of steel and 5 copper inside the flat side and underlying both edges of a slot in which the ground off portion is welded, while spaced from both adjacent corners of the flat side. Further, in making such shafts in accordance with the patents mentioned, the 10 shaft has been formed completely with a slot in the middle of the side in question and it has been necessary to make relatively expensive welding strips of steel or combined steel and copper, to subject the shaft with the strip inserted therein 15 to an ironing operation to position the strip preparatory to wrapping and welding, and after welding to grind off the protruding portion of the strip. Thus, due not only to the steps required, but the cost of material in the strips, such shafts 20 have been relatively expensive to produce, while the shafts themselves have also been subject to objections as regards weight, balance, resiliency and appearance.

My invention has among its objects to provide 25 an improved polygonal or hexagonal shaft of this type having an improved and lighter welded section of an improved lapped seam construction and disposed in an improved location, and such a shaft which is better balanced and has increased re- 30 siliency, at the same time that it has an improved appearance and is capable of being produced at a very substantially reduced cost. A further ob- 35 ject of my invention is to provide an improved method of making such shafts, whereby it is made 40 possible to finally shape the shaft, portion by portion, in a progressive manner during the several forming operations performed on the blank, so that as the blank is operated on each part thereof 45 is given its ultimate shape in the finished shaft, thus to eliminate various steps and operations in the previous methods and especially those steps 50 of the previous methods which required grinding away steel projections and longitudinally grooving or otherwise drastically reshaping the shaft 55 following the welding of the same and, by im- proved steps, reduce the weight and expense of the metal used in the welded section and sub- stantially facilitate the manufacture of such shafts, while also substantially reducing the cost 60 of manufacture and producing an improved shaft.

Still further objects of my invention are to provide an improved welded strip and improved blanks adapted to be formed in the various steps of my improved method and used with my improved strip in an improved manner. These and other objects and advantages of my improved construction will, however, hereinafter more fully appear.

In the accompanying drawing, I have shown for purposes of illustration one embodiment of my improved shaft and of my improved method for producing the same, with the several improved blanks and the improved welding strip also being illustrated in connection with the latter.

In the drawing,

Figure 1 is a plan view of the first form of flat blank;

Fig. 2 is a plan view of the same after the first forming operation;

Fig. 3 is an end view of the blank shown in Fig. 1;

Fig. 4 is a combined view showing enlarged opposite end views of the larger and smaller ends of the blank after the first forming operation;

Fig. 5 is a similar view showing those ends after the second forming operation;

Fig. 6 is a similar view after the third forming operation;

Fig. 7 is a similar view showing the same after the fourth forming operation;

Fig. 8 is a similar view showing my improved welding strip drawn into the blank shown in Fig. 7;

Fig. 9 is a plan view of a blank wrapped in asbestos ready for the welding operation;

Fig. 10 is a top plan view of the finished shaft;

Fig. 11 is a view similar to Figures 4 to 8 showing the opposite ends of the welded shaft;

Fig. 12 is a plan view of my improved welding strip shown in Fig. 8;

Fig. 13 is an enlarged end view of the same, and

Fig. 14 is an enlarged perspective view of this strip.

Referring first to my improved method, it will be noted that I first form a flat tapered blank 1, shown in Figures 1 and 3, which is of any desired length and formed of a thin sheet of steel having smooth imperforate like edge portions, although the thickness is, of course, subject to variation as in previous methods.

This blank 1 is first subjected to a series of forming operations, herein, as preferably, four in number and acting to form the body of the shaft, step by step into hexagonal form while providing

means for producing a new and effective weld between the flat generally parallel edge portions in a new location along one edge of a flat side and terminating at a corner.

5 Of these, the first is preferably a press operation which is performed slightly to one side of the center of the blank. It results, as shown in Fig. 4, in the complete forming of the lower half of the hexagonal shaft, i. e. in forming the three 10 lower flat faces 2 of the shaft and the two lower corners 2', while also forming upstanding tapered sides 3 and 4 of different width with the side 3 substantially wider than the side 4. Herein, where a shaft is being made which, while hexagonal substantially throughout its length, is also round for a short distance at its head carrying extremity, it will also be noted that at the latter end the lower round half of the shaft is also formed in this operation, as shown at 5. As 15 20 regards the sides, it will also be noted that the sides 6 and 7 of the round portion 5 are also tapered and of different width, with the side 7 wider than the side 6, while these sides also diverge slightly from one another above a transverse line 25 30 passing through the center of the shaft above the formed portion thereof. The sides 3 and 4 in the hexagonal portion of the shaft, on the other hand, extend vertically upward above the line 8 as shown at one end of the blank, and, of course, merge into the sides 6 and 7 toward the other end of the blank.

The second forming operation, which also is preferably a press operation in which dies press the sides 3, 4 toward one another, results, as 35 shown in Fig. 5, in further forming the hexagonal section of the shaft by completing corners 9 at the line 8 and bending the sides 3, 4 toward one another. Here, it will be noted that the wide side 3 and narrow side 4 are bent inward to an 40 equal extent so that an extension of the side 4 would intersect the side 3 in a vertical line extending through the axis. Thus, two additional corners and two additional flat surfaces are formed at the same time that the upper extremities of the 45 sides 3 and 4 are disposed above what will be the remaining flat surface. At the round end of the blank, the sides 6 and 7 are also similarly bent toward one another, at the same time that the round forming operation is carried further or 50 higher in the same manner as in the hexagonal forming operation previously described, the short side 6 here being also so disposed that an extension thereof would intersect the end of the longer side 7.

55 The third forming operation, which is also preferably a press operation, leaves the side 4 undisturbed, as shown in Figure 6. However, in this operation, the side 3 is bent downward over the side 4 into overlapping relation abutting the latter 60 adjacent the edge thereof, while the side 3 is also bent to form a corner 10 between it and the next adjacent lower flat surface, thus also carrying further the hexagonal forming operation. At the same time, the side 8 on the round end of the blank is bent further inward into substantially 65 round form with its edge under and located substantially below the edge of the side 7, while the round forming operation is also carried slightly higher on the latter and the upper end of this side is slightly lowered.

70 The fourth forming operation, which is a closing operation, and also preferably performed in a press, results, as shown in Figure 7, in bending the remainder of the side 4 downward and forming the last remaining corner 11, while also form-

ing a short laterally and inwardly projecting horizontal supporting edge portion 12 of the remainder of the side 4. Here, it will also be noted that the side 3 is brought into resilient engagement with the edge 12, and that the portion 3 is slightly angularly disposed just above parallelism with the corresponding opposite, or bottom, flat face 2. Thus, it will be noted that a lateral welding strip receiving opening is provided leading inward to the inner edge of the portion 12 which is resiliently engaged by the lower surface of the part 3 at a point spaced from the edge thereof. It will also be noted that herein, as in practice, the portion 3 is of such slightly greater length than this edge 12 that the extremity of the portion 3 is located slightly beyond the corner 11. At the opposite or round end of the blank, it will also be noted that the end 7 is further rounded and brought down so that it is just above the edge of the portion 6, though with a slight welding strip receiving gap therebetween, since this portion of the shaft is formed on a radius.

With the body of the blank thus formed in an improved manner into hexagonal and round portions, the next step is the insertion of an improved welding strip between the overlapped edges 3, 12 and 6, 7. This strip herein is in the form of a thin shim 13 of suitable welding metal such as copper. In a preferred form, the same has a thickness of .003 of an inch, although the thickness may be varied, slightly thicker or thinner strips, for example, between .001 and .005, being usable under varying conditions. Herein, this shim is also entirely flat and quite narrow, a width of $\frac{1}{32}$ of an inch being found well suited to my purpose. If desired, this shim may be inserted between the overlapping edges from the side upon slightly springing the edges apart but the same is preferably inserted by drawing the same in longitudinally between the overlapped portions 3, 12 and 7, 6. Further, it will be noted that, since the overlapping portions in the hexagonal portion of the shaft press toward each other, these engage and hold the shim 13 in position between the same and thus eliminate all necessity for providing any means for retaining the shim in position. Ordinarily, with the shim thus positioned in the hexagonal portion of the blank by the spring pressure of the edges, 50 the same when thus inserted is also retained in position by the portions 7, 6 in the shorter rounded portion of the blank. As regards the lateral position of the shim 13 between the overlapping portions, it will also be noted that at 55 one end one edge of the shim is preferably disposed slightly within the outer edge of the portion 3 while extending increasingly beyond the latter toward the other end of the blank, and that the shim is preferably of such width as to extend throughout its length beyond the opposite extremity of the edge portion 12 by an amount substantially equal at the width of that edge, as shown in Fig. 8. This arrangement, while requiring a minimum of copper to be inserted 60 between the overlapped edges and thus producing a desirable metal to metal copper-steel alloy weld, is further very effective since it results in only a minimum of copper on the exterior of the shaft after welding.

After the insertion of the shim 13 and while the latter is held in place by the holding action of the edges, as shown in Fig. 8, the blank is next ironed to bring the portions 3, 12 and 6, 7 into their final position ready for welding, and 75

then is wrapped in asbestos tape, as shown in Fig. 9. After being so wrapped, the blank is then welded, preferably in a suitable hydrogen atmosphere, in such manner as to cause the copper 5 in the shim 13 to be melted and unite the overlapped edge portions in a secure uninterrupted metal to metal copper-steel alloy weld throughout the length of the blank as shown in Fig. 11. The welded shaft is next heat treated and also 10 straightened, if necessary, and then polished, the extremity of the portion 3 which projects beyond the corner 11, also preferably being polished off in this operation to complete the formation of the hexagonal shaft, while the edge of the 15 portion 7 of the rounded portion of the shaft is similarly removed. Obviously, of course, the shaft may thereafter be suitably coated or plated as desired to prevent rust or to apply any desired finish to the same.

20 As a result of my improvements, it will be noted that a shaft is produced, which has a substantially lighter welded section and is therefore better balanced and has greater resiliency, the weight of my entire welded section including 25 the overlapped portions and the welding material being less than the weight of merely the strips heretofore added to the shaft. Further, due to my improved welded section, and the location of the same at a corner with two edges 30 of the shaft united together, a stronger shaft is produced. At the same time a more attractive shaft is produced, the location in the corner making the joint far less noticeable than a joint in the middle of a flat hexagonal surface. In 35 addition, a shaft may be produced at substantially less expense, the saving amounting to several cents per shaft. As regards the method, it will also be noted that it is possible to finally shape the several parts of the shaft as the blank 40 is operated on to form the finished shaft in a series of simple inexpensive press operations and while using a simple and inexpensive flat welding strip and thus eliminate the expensive steps of reshaping the shaft following the welding operation or forming either a steel strip or a combined steel and copper strip, while also reducing the amount and cost of the material in the strip. Further, after the insertion of the 45 strip and due to the fact that the strip is held by the resilient action of the edges, it will be observed that all necessity for providing any holding means on the strip is eliminated. Thus all interlocking members at the overlapped joint are eliminated and a homogeneous alloy weld is 50 provided between the like smooth edge portions which forms the sole connection between these overlapped portions. Due to the shim used, wider than the overlap, the shim is also sufficiently strong to permit a simple and easy drawing in 55 operation without breakage. The fact that no portion of the strip remains on the exterior of the shaft, also eliminates any necessity for grinding off the same. These and other advantages of my improved construction will, however, be apparent to those skilled in the art.

In carrying out my invention, it will be evident that if desired, a shaft may be produced which is hexagonal in cross section throughout its length, as distinct from rounded at its head 70 carrying end, as described herein. Also if it is desired to round the shaft at the grip carrying end, such a shaft may be readily formed by also forming the grip carrying end in a manner similar to the rounded head carrying end and in the 75 same operations herein described. It will, of

course, also be evident that if, for any reason, it is desired to extend the rounded portion above the head carrying end or below the grip, this also may be done. Of course, if desired, a wholly round form of shaft may also be produced, by applying to the whole shaft the forming operations described herein in connection with the round end of the shaft shown herein, although I prefer to make such wholly round shafts in accordance with the teachings of a companion application filed under even date herewith.

While I have in this application specifically described one embodiment of my improved shaft, and one method of making the same, it will be understood that these forms of the same are so shown for illustrative purposes and that my invention may be modified and embodied in various other forms without departing from its spirit or the scope of the appended claims.

What I claim as new and desire to secure by Letters Patent is:—

1. A golf or other shaft having a tapered polygonal sheet metal body portion and a welded section having its exposed joint wholly in one corner of said polygonal body between adjacent overlying portions.

2. A golf or other shaft having a tapered polygonal sheet metal body portion having an uninterrupted periphery and a welded section in said periphery having an overlying edge portion adjacent one corner and having its extremity terminating substantially in the plane of an adjacent face.

3. A golf or other shaft having a tapered polygonal sheet metal body portion and a welded section having its exposed joint wholly in one corner of said polygonal body, and an inner reinforcing and supporting strip on an adjacent flat side.

4. A golf or other shaft having a tapered polygonal sheet metal body portion and a welded section comprising an overlapping smooth imperforate edge portion of one flat face thereon and an edge portion formed on an adjacent corner having laterally extending means underlying said first mentioned edge portion and welded thereto.

5. A golf or other shaft having a tapered polygonal sheet metal body portion having an unobstructed bore and an exposed joint wholly in one corner of said polygonal body including an overlying edge portion formed on the extremity of one face and an inner reinforcing strip formed on the edge of an adjacent face and underlying said overlying edge portion.

6. A golf or other shaft having a tapered sheet metal body portion of polygonal cross section throughout a portion of its length and rounded cross section throughout the remainder of its length, and having a welded section extending longitudinally thereof and comprising aligned overlapping flat and rounded portions.

7. A golf or other shaft having a tapered sheet metal body portion of polygonal external and internal cross section throughout a portion of its length and rounded external cross section throughout the remainder of its length, said shaft having said portion of rounded cross section at the smaller end of the same.

8. A sheet metal blank for golf or other shafts comprising a tapered trough like body portion of polygonal cross section at its bottom throughout a portion of its length, and of rounded cross section at its bottom throughout the remainder of its length, and also having upstanding verti-

- cal and diverging tapered sides of different height above said sections respectively.
9. A blank for golf or other shafts comprising a tapered body portion of polygonal cross section 5 at its bottom throughout a portion of its length, and of rounded cross section throughout the remainder of its length, and also having tapered sides of different height extending above said polygonal and rounded portions and toward one another.
10. A blank for golf or other shafts comprising a tapered body portion of polygonal cross section substantially to its top, and having a laterally deflected tapered face forming portion 15 overlying its top and a relatively angularly disposed narrower tapered face forming portion having its upper edge underlying the free edge of said first mentioned portion.
11. A blank for golf or other shafts comprising a tapered body portion of polygonal cross section substantially to its top throughout a portion 20 of its length and a body portion of rounded cross section throughout the remainder of its length, and having laterally deflected tapered edge portions 25 overlying the top of said polygonal and rounded portions, and relatively angularly disposed narrower tapered edge portions having their upper edges underlying the free edges of said first mentioned portions.
- 30 12. A blank for golf or other shafts comprising a tapered sheet metal body portion of polygonal cross section from top to bottom, and having an underlying edge portion on one corner thereof, and a face portion projecting laterally 35 from an adjacent corner and overlying said edge portion, said polygonal cross section extending throughout a portion of the length of the blank and the remainder of the length thereof being of rounded cross section with overlapping edges.
- 40 13. The method of making golf or other shafts which consists in, forming a sheet metal blank of polygonal cross section having flat overlapping smooth edge portions on adjacent faces, and welding said overlapping flat portions together 45 with the overlying edge portion terminating at the corner between said faces.
14. The steps of making golf or other shafts which consist in, forming a sheet metal shaft blank of polygonal cross section having like 50 tapered overlapping smooth imperforate edge portions on adjacent faces resiliently engaging each other, and inserting a shim of welding material between the resiliently engaging overlapping edge portions.
- 55 15. The steps of making golf or other shafts which consist in, forming a sheet metal shaft blank of polygonal cross section having like resiliently engaging tapered overlapping smooth imperforate edge portions on adjacent faces, and 60 inserting a flat shim of welding material between the overlapping portions, with portions of said shim extending laterally beyond the underlying edge inside the blank and laterally beyond the overlying edge outside the blank toward the 65 smaller end of the latter.
16. The steps of making golf or other shafts which consist in, forming a polygonal shaft blank having substantially parallel overlapping flat face portions resiliently engaging one another at one corner of the blank, inserting a shim of welding material between said portions, ironing said portions, at said corner, and welding the blank while 70 said flat face portions are pressed together to form a seam in said corner.
17. The method of making tapered polygonal golf or other shafts which consists in, progressively forming the different face portions from the bottom toward the top of the blank, forming one side face while forming an inwardly projecting edge portion thereon resiliently engageable with the top face and supporting the latter, and welding said edge portion to the edge portion of 5 said top face.
18. The steps of making tapered polygonal golf or other shafts having welded overlapped seams which consist in, finally shaping the several portions of the shaft body by progressively forming different face portions of the polygonal tapered body thereof in successive steps while forming a 15 tapered overlapping edge portion adapted to form the last face and an overlapped support therefor formed on the extremity of an adjacent face, whereby to produce the ultimate shape of said shaft prior to welding the same. 20
19. The steps of making tapered polygonal golf or other shafts which consist in finally shaping the several portions of the shaft body by progressively forming different face portions of the polygonal tapered body thereof in successive steps while forming a 25 tapered overlapping edge portion adapted to form the last face and resiliently engaging an overlapped support therefor formed on the extremity of an adjacent face, drawing in a shim of welding material between said resiliently engaging overlapping portions, and welding 30 said portions together.
20. The method of making golf or other shafts which consists in, forming a sheet metal blank having like smooth imperforate edge portions into a tapered body of final cross section throughout a substantial portion of the periphery thereof, said finished peripheral portion comprising longitudinally extended angularly related surface portions spaced from the edges of the blank, and subsequently similarly shaping the remainder of the blank including the portions adjacent the edges into final cross section with the angularly related smooth surface portion formed on one edge portion overlying the like opposite edge portion and terminating at a corner formed adjacent the latter edge portion. 35
21. The steps of making polygonal golf or other shafts which consist in, forming a flat tapered blank, pressing the same at one side of its longitudinal center line to form a finished portion of a polygonal body while forming above the latter incomplete portions of said body including upstanding tapered sides of different height 40 throughout their length, bringing said sides into overlapping resiliently engaging relation while further forming said polygonal body, inserting a shim of welding material between the overlapped portions, ironing said portions, wrapping the 45 blank in asbestos, and welding the same. 50
22. The method of making polygonal golf or other shafts which consists in, forming a flat tapered blank having like smooth imperforate edge portions, pressing the same at one side of its longitudinal center line to polygonal form to finish the lower half of the polygonal body while forming above the latter upstanding tapered flat sides, bringing said sides into overlapping generally parallel relation while shaping them into polygonal form and while bringing the seam into one corner, and welding the overlap to form the 55 seam in said corner. 60
